SPLIT CRADLE FOR TUBULAR STRANDING MACHINES

Carl O. Bruestle, Metuchen, N. J., assignor to
Synero Machine Company, Perth Amboy, N. J.,
a corporation of New Jersey

Application July 1, 1950, Serial No. 171,739

4 Claims. (Cl. 57—58.34)

1

The present invention relates to tubular stranding machines and especially to a cradle construction for supporting a spool or reel of wire in such a stranding machine. Tubular stranding machines of the type to which this invention is applied comprise a large tube within which a cradle is mounted, which cradle is supported on bearings and remains stationary as the large tube rotates about it. The cradle in turn supports a spool or a reel of wire which is fed through the machine by means of a drawing capstan being twisted by a twisting head.

Since the tubes are very large and since the reels of wire must be frequently replaced, the tube is provided with openings to permit the withdrawal of an empty reel and the insertion of a full reel. Moreover, in the usual construction, the openings in the tube above described are made sufficiently large so that the cradles may be inserted therethrough.

My present invention makes it possible to utilize smaller openings in the strander tube, thereby increasing its strength while at the same time permitting the ready assembly of the machine since the cradle can be inserted through the smaller opening. This is accomplished by making a cradle which, instead of being a unitary structure, is formed in a number of pieces which can be more readily inserted through the smaller tube opening.

It is an object of the invention to provide a cradle for a tubular strander which may readily be inserted through the normal openings of a stranding machine tube.

It is another object of the invention to provide such a cradle which is made in two or more parts.

It is a further object of the invention to supply a cradle which may readily be inserted through the corresponding opening in the stranding machine tube and assembled within the tube.

Other objects and features of the invention will be apparent when the following description is considered in connection with the annexed drawings, in which—

Figure 1 is a horizontal, sectional view of a single section of a wire stranding machine showing my split cradle construction in place within the section;

Figure 2 is a vertical, cross-sectional view of the machine of Figure 1 showing particularly the mode of mounting the two cradle sections on their supporting bearings; and

Figure 3 is a vertical, cross-sectional view

taken on the plane of the line 3—3 of Figure 2 and showing details of the construction of the strander cradle and of its fastening to one of the supporting bearings.

Referring now to the drawings and particularly to Figures 1 and 2, there is shown at 10 the usual strander tube having therein the elliptical openings 11, Figure 3, through which reels of wire or the like may be inserted. As is indicated by the dot-dash line 12, Figure 1, I prefer that the openings in tube 10 be elliptical in shape since this provides for a maximum of strength in the tube 10.

Mounted within the tube 10 is the cradle comprising the two portions 13 and 14, each of which is provided with a bearing 15 in which the shaft 16 is supported. A spool or reel of wire generally designated 17 is in turn supported upon the shaft 16 in the usual manner.

Each portion 13 or 14 of the cradle of my invention is of a generally U-shaped form and is provided at either end with flange portions, respectively designated 18 and 20. These flange portions are provided with bores through which bolts 21 may be inserted, the bolts being threaded into a block 22 rectangular in cross section, the block 22 being in turn suitably supported by ball bearings as indicated particularly at 23, Figure 2.

It will be seen that since the cradle need not be inserted as a unit, it is possible to utilize smaller openings 11 and to assemble the two halves 13 and 14 of the cradle structure to the blocks 22 after the portions 13 and 14 have been passed through the openings and are positioned within the tube 10. This is done without any modification of the structure since such tubular stranding machines are invariably supplied with a plurality of openings 11 spaced circumferentially around the tube in order to assure balance of the tube which rotates at relatively high speed and to prevent the setting up of strains in the tube. Thus, the assemblage is facilitated since the bolts 21 may be readily threaded into the blocks 22 and thus fasten the cradle members 13 and 14 to the bearing blocks.

It has been pointed out in this embodiment of the tubular stranding machine that the openings for the insertion of the wire cradles should be made elliptical for the advantages derived therefrom in permitting the construction of tubes considerably stronger than those using conventional openings. I have found that in making the elliptical openings a ratio of major to minor axis of about 1.5 to 1 produces desirable

results in that it permits the making of an opening large enough to accept a standard size reel without removing an excessive amount of material from the standard tube. When the ratio of the major axis to the minor axis is increased beyond about 2 to 1, though strength of the tube is not materially impaired, this works an unnecessary elongation of the opening for acceptance of the substantially circular wire spool and rectangular cradle. The relationship between the elliptical opening or axes thereof and the spool to be used in the operation is such that a rectangle corresponding in size to the projection of the spool onto a plane should be capable of being inscribed within the ellipse. The advantages derived from this elliptical opening apparatus in combination with the split cradle are apparent in that it permits simple and rapid changing of spools and assembly of the parts for stranding operations.

It has been found that stranding machines constructed in accordance with this invention wherein the ratio of the major to minor axes of the elliptical openings is kept within the range of 1.5 and 2 to 1 permits operation of the machines at speeds 50 per cent higher than previous machines of substantially similar design employing conventional rectangular openings.

While I have described a preferred embodiment of my invention, it will be apparent to those skilled in the art that the details comprising the invention herein disclosed are capable of some modification and I do not therefore desire to be limited to the illustrated embodiments but only as required by the appended claims.

What is claimed is:

1. A reel supporting cradle structure for a tubular stranding machine of the type having a plurality of tubular sections arranged end to end and a cradle in each section, comprising, in combination, bearings mounted on the axis of each section at the ends thereof, bearing blocks rotatably mounted on each bearing, a pair of cradle sections of generally U-shape and having flanges at the ends of the arms of said U, means for fixing said cradle flanges on said bearing blocks with one of said cradle sections on either side of said bearing blocks, and reel supporting means located substantially centrally of the upper edge of each cradle section whereby a reel arbor may be mounted therein with the reel flanges extending between the bases of said U-shaped cradle sections.

2. A reel supporting cradle structure for a strand handling machine having a plurality of sections and a cradle mounted in each section, comprising in combination bearings mounted on an axis in each section, bearing blocks rotatably

mounted on each bearing, a pair of cradle sections of generally U-shape, having flanges at the ends of the arms of said U, means for fixing said cradle flanges on said bearing blocks with one of said cradle sections on either side of said bearing blocks, and reel supporting means located substantially centrally of the upper edge of each cradle section, whereby a reel arbor may be mounted therein with the reel flanges extending between the bases of said U-shaped cradle section.

3. A reel supporting cradle structure for a stranding machine of the type having a plurality of sections arranged end to end and a cradle in each section, comprising in combination, bearings mounted on the axis of each section at the ends thereof, bearing blocks rotatably carried on each bearing, a pair of cradle sections having flanges at the ends thereof for fixing said sections to said bearing blocks with one of said cradle sections on either side of said bearing blocks, and reel supporting means substantially midway between the ends of said cradle sections whereby a reel arbor may be mounted therein with the reel flanges extending between the sections of said cradle.

4. A reel supporting cradle structure for a strand handling machine having a plurality of sections and a cradle mounted in each section, comprising in combination bearings mounted on an axis in each section, bearing blocks rotatably mounted on each bearing, a pair of cradle sections having the ends thereof parallel to the axis of said section, flanges at the ends of each of said cradle sections, and means for fixing said cradle flanges on said bearing blocks with one of said cradle sections on either side of said bearing blocks, and reel supporting means located substantially centrally of each cradle section, whereby a reel arbor may be mounted therein with the reel flanges extending between the sections of said cradle.

CARL O. BRUESTLE.
